(57) **CLAIM**

The ornamental design for a padded base drum harness, as shown and described.

DESCRIPTION

FIG. 1 is a perspective view thereof,

FIG. 2 is a front side view thereof,

FIG. 3 is a back side view thereof,

FIG. 4 is a left side view thereof,

FIG. 5 is a bottom side view thereof; and,

FIG. 6 is a top side view thereof.

The right side is symmetrical to the left side. In the drawings, the broken lines are for the purpose of illustrating environment only and form no part of the claimed design.
